CLAIM

The ornamental design for a flowline support device, as shown and described.

DESCRIPTION

FIG. 1 is a perspective view of a flowline support device in accordance with the new design shown supporting a section of pipe;

FIG. 2 is another perspective view of the flowline support device;

FIG. 3 is a bottom view of thereof;

FIG. 4 is a front view thereof;

FIG. 5 is a rear view thereof;

FIG. 6 is a left-side view thereof;

FIG. 7 is a right-side view thereof;

FIG. 8 is a top view thereof;

FIG. 9 is a cross-sectional view taken along section 9-9 in FIG. 8;

FIG. 10 is a top view of a second embodiment thereof;

FIG. 11 is a cross-sectional view of the second embodiment taken along section 11-11 in FIG. 10;

FIG. 12 is a top view of a third embodiment thereof;

FIG. 13 is a cross-sectional view of the third embodiment taken along section 13-13 in FIG. 12; and,

FIG. 14 is a perspective view of a fourth embodiment of a flowline support device in accordance with the new design. The broken lines represent environment of use and form no part of the claim.
